(57) **CLAIM**

The ornamental design for a nasal dilator, as shown and described.

DESCRIPTION

FIG. 1 is a perspective view of a nasal dilator showing our new design;

FIG. 2 is an enlarged view of the left side of the nasal dilator shown in FIG. 1 taken along line 2;

FIG. 3 is an enlarged view of the right side of the nasal dilator shown in FIG. 1 taken along line 3;

FIG. 4 is a front view of the nasal dilator;

FIG. 5 is an enlarged view of the left side of the nasal dilator shown in FIG. 4 taken along line 5;

FIG. 6 is an enlarged view of the right side of the nasal dilator shown in FIG. 4 taken along line 6;

FIG. 7 is a back view of the nasal dilator;

FIG. 8 is an enlarged view of the left side of the nasal dilator shown in FIG. 7 taken along line 8;

FIG. 9 is a top view of the nasal dilator;

FIG. 10 is an enlarged view of the left side of the nasal dilator shown in FIG. 9 taken along line 10;

FIG. 11 is an end view of the right side of the nasal dilator;

FIG. 12 is an enlarged view of FIG. 11;

FIG. 13 is an end view of the left side of the nasal dilator; and,

FIG. 14 is an enlarged view of FIG. 13.

The broken line shown in FIGS. 1-14 illustrate portions of the nasal dilator that form no part of the claimed design. The broken lines immediately adjacent to the shaded areas represent the boundaries of the claimed design. None of the broken lines form part of the claimed design.
